 International Business Machines Corporation,
 New York, N. Y., a corporation of New York

Application May 16, 1936, Serial No. 80,040

25 Claims. (Cl. 209—110)

This case relates to accounting machines, particularly a sorter, controlled by record cards.

The record cards have parallel columns of index point or perforation-receiving positions, selectively perforated according to a predetermined code to represent information. According to the Hollerith code, used here, a single index point in a column is perforated to represent an item. There are twelve index points in a column, and, thus, a perforation in one index point, according to the Hollerith code, may represent values 9 to 0, 11, and 12. Each card column may be referred to as a card field. Also, a series of adjacent columns containing a multi-denominational order value may be referred to as a card field, particularly, as a multi-order field.

The usual function of a sorter is to separate a stack of record cards according to the perforations in a selected card column. At the end of an operation of the sorter, all cards having the same perforation in the selected column will lie in one sorting pocket. This may be called straight, simple, or ordinary sorting.

The object of the present invention is to place the sorting operation under control of a value comparing means.

Further, the object is to sort to different pockets or segregate cards into various groups according to a comparison of different values.

Still further, the object is to control sorting according to a comparison of a card value with a related pre-set or fixed value.

Another object is to control sorting according to a comparison of two related values, both taken from the cards.

More specifically, the object is to segregate cards having a greater value than a related value into one group, cards having a lesser value than the related value into another group, and cards having a value equal to the related value into still another group.

An object is also to provide means for causing the sorter to effect straight sorting if the compared values have one relation and to effect modified sorting if the compared values have a different relation.

Another object also is to provide means for adjusting the comparing means to select different sorting arrangements for similar value comparing results.

Other objects will appear from the following parts of the specification and from the drawings.

Fig. 1 is a section through the control part of the sorter.

Fig. 1a shows a part of the record card.

Fig. 2 shows one order of a settable value commutator.

Fig. 3 is a plan view taken along lines 3—3 of Fig. 1.

Fig. 4 is the circuit diagram of one form of the invention, and

Fig. 5 is the circuit diagram of another form of the invention.

The invention has been disclosed in connection with the sorting machine shown in Patent No. 1,880,428, although it is understood that the invention is also applicable to any other suitable card sorting machine.

As premised above, simple, ordinary, or straight sorting is the operation of sending the cards to different pockets according to the values sensed in one selected card column. Sorting to pockets selected by a comparison of values may be referred to as modified, deviated, relative, compared value sorting or as sorting directed or selected by a comparison sensing or comparison value analysis.

Two forms of the invention have been disclosed, the circuit of one being shown in Fig. 4 and the circuit of the other being shown in Fig. 5. In either form, if one card field bears a greater value than another card field or than a set up value, the card may be sent to one destination. If the first card field bears a less value than another card field or the pre-set value, then the card may be sent to another destination. If the card fields bear equal values or if a card field and the pre-set value are equal (when comparison is between one field and the pre-set value), then the card may be sent to still another destination.

In the form shown in Fig. 5, it is also possible to effect straight sorting if the compared values bear a certain selected relationship, to send the cards to one destination if the compared values bear a different relationship, and to send the cards to still another destination if the values are equal.

The record card has twelve perforation receiving or index point positions which from the bottom to the top of the card are the 9, 8, 7, —1, 0, 11, and 12 positions, as indicated in Fig. 1a.

There are thirteen card receiving pockets in the sorting machine, twelve of which correspond to the index point positions 9, 8—0, 11, and 12 and may be referred to as the 9, 8—0, 11, and 12 pockets; the thirteenth pocket is known as the reject pocket for receiving cards which do not go into any of the other pockets. (Only the 9 pocket is shown herein.) In ordinary sorting,

- the cards are sent to these pockets according to the perforations in one column of each card. The present machine is capable of straight sorting and also of comparison-controlled sorting.
- 5 In the latter operation, the compared values in any denominational order may be any one of values 1 to 9 and their corresponding index point positions 1 to 9, and no comparison is needed or made between the 11 and 12 positions of the card 10 fields.
- 10 Referring to Figs. 1 and 3, the machine comprises a hopper 160 in which the stacked cards T are placed. Driven by a motor SM (see the circuit diagrams, Figs. 4 and 5) is a shaft 161 below the hopper. Shaft 161 has an eccentric connection to a link 162 connected to an arm 163 which has a swivel connection to a picker 164. Each revolution of shaft 161 oscillates arm 163 to reciprocate picker 164. On the forward stroke 15 of the picker, it feeds the bottom card out of hopper 160 and to feed rolls 165 which advance the card to the analyzing station. Ordinarily the sorter has a single sensing brush SB at the analyzing station to sense any one of the card 20 columns. In the present case, there are a plurality of sensing brushes SB, preferably one for each card column. These brushes coat with a common rotating contact roller 166. In ordinary sorting, only one brush SB is in operation to 25 control sorting according to the item designations in one card column, as will be further explained in connection with the circuit diagrams.
- 30 Feed rolls 165 continuously feed the card through the analyzing station comprising brushes SB and roller 166, along a table 168, and into the grip of upper and lower feed rolls 169. The shaft of the lower feed rolls rigidly carries a series of spirally arranged cams 170. Each cam 170 underlies and supports a pivoted arm 171 biased 35 downwardly by a spring 172. Each arm 171 supports the entrance end of a different one of the guide blades 173 which lead to the card receiving pockets. The entrance ends of the blades are of 40 spring metal having a normal downward bias to cause the entrance ends to follow the downward movement of their associated arms 171.
- 45 During rotation of cams 170, they successively release the arms 171 for depression by their individually connected springs. The release of the 50 several arms 171 is synchronous with the successive analysis by the sensing brushes SB of the index point positions of the card. When the brush senses a perforation, it causes a circuit, which will be traced later, to be momentarily made through a sorter magnet 175. The latter attracts its armature 176 to release a latch plate 177 extending across all the arms 171, and a spring 178 thereupon rocks plate 177 counter-clockwise to set its nose 177' underneath the projections 179 of those arms 171 which are still in upper position. The nose 177' simultaneously engages in notches 180 of the arms 171 which have already dropped. Thus, whenever a perforation is sensed some of the blades will be 55 locked down and the others held up by latch plate 177. The entrance ends of guide blades 173, which follow the action of their associated arms 171, will correspondingly be separated to leave a passage for the card.
- 60 70 In ordinary sorting, after a card leaves the brushes SB, its leading end enters the passage formed between the entrance ends of the guide blades and is thereby routed to the pocket corresponding to the sensed perforation. If no perforation has been sensed, all the entrance ends

are in down position by the time the card reaches them, and the card as it moves off the table 168 rides over all the blades 173 and is fed by successive pairs of feed rolls (not shown), driven by the sorting motor SM, to the reject pocket.

After a card has been analyzed and has just entered the passage between two guide blades 173 selected by the analysis and before the next card reaches the analyzing brushes SB, a pair of duplicate cams 182, one at each side of cams 170, moves a bail 183 to the right (Fig. 1) to cause the bail to rock plate 177 clockwise, thereby re-latching the plate with respect to the meanwhile released armature 176, and also releasing nose 177' from restraint on arms 171. Arms 171 are, thereupon, restored to upper positions by cams 170 as the latter complete their cycle and return to home position.

The mechanical features of the machine having been described, its operation will now be explained further with reference to the circuits.

To start the machine in operation after a stack of cards has been placed in magazine 160 and main switch 185 closed, the operator depresses start key 186 of a lever 187 against resistance of a spring 188. The lever rigidly carries an insulating block 189 initially between a pair of contact blades 190 and separating the coacting contacts 191 carried by the latter blades.

The key 186 is held down until the first card reaches a card lever 192. The pressure of the card on lever 192 causes the latter to maintain contacts 191 closed after the operator releases key 186. The successive cards continue to act on lever 192 so as to maintain contacts 191 closed. Thus, as long as cards are feeding, contacts 191 remain closed.

Closing of contacts 191 completes a circuit through a pair of relays 193 and 194. The latter close their respective contacts 193a and 194a, 40 at opposite sides of the sorting motor SM, to complete the circuit through the motor.

The first form of the invention, the circuit of which is shown in Fig. 4, will now be explained.

The sensing brushes SB, for purposes of the present invention, are each connected to double plug sockets 195. For single column, straight sorting, the operator runs a plug wire 196 from a plug socket 197 to the plug socket 195 of the brush SB for reading the selected control column. Further, a switch 198 is opened and a switch blade 199 is set in upper, ordinary sorting position, engaged with switch terminal 199a which is directly connected with the right side 55 of the supply line. This is all that need be done to set the machine for ordinary sorting in the embodiment shown in Fig. 4.

When a perforation in the selected control column of a card is sensed by the associated brush SB, the following circuit is formed:

Circuit a—Ordinary sorting

From the right side of the supply line, through switch 199—199a, sorter magnet 175, lead 200, 65 plug socket 197, plug wire 196, the selected plug socket 195, the connected brush SB, the contact roller 166, through the usual commutator 201, and to the left side of the supply line.

Circuit a energizes magnet 175 to cause the 70 card to be routed to the pocket selected by the analyzed perforation.

Comparison sorting according to the form of the invention shown in Fig. 4 will now be explained.

It is desired to send a card to the 11, 12, or reject pocket depending on the relation of two compared values. These values may both be taken from the record card. Alternatively, one of the values may be taken from a manually settable commutator 560. Either the commutator or the card may be referred to broadly as a value bearing source. Fig. 2 shows one order of the commutator 560. Each order includes an indicating wheel 561 rotatably mounted on a shaft 561' and the numbers 0 to 9 of which are viewed through a sight opening 562. To the side of each indicating wheel 561 is fast a gear 563 which through an idler gear 564 rotates a gear 565. Carried by gear 565 through insulation is a feeler 566 bent to constantly engage a common contact ring 567 of a stationary commutator disk 568. Disk 568 has ten contact segments 569 insulated from each other and 20 from ring 567. Each of segments 569 corresponds to one value position of indicating wheel 560. Thus, if a wheel 561 is adjusted to read "1", feeler 566 will be moved into engagement with the segment 569 corresponding to value 7. Each 25 order of the settable commutator may be separately adjusted to set the associated feeler 566 in engagement with a desired value segment 569.

As many orders of the commutator 560 may be provided as is desired. In the circuit diagrams, four orders of commutator 560 are diagrammatically shown.

An emitter E, associated with the settable commutator, has contact spots 570 corresponding to values 9 to 0. The spots corresponding to values 35 9 to 0 are wired to all the contact segments 569, of the several orders of commutator 560, which correspond to the same value. Thus, all the "9" segments 569 are wired in series with each other and with the "9" spot 570 of emitter E. The 40 shaft 571 of emitter E carries diametrically opposite and conductively connected brushes 572. Shaft 571 is driven counterclockwise by the sorter motor SM in 1:2 ratio with the shaft of sorting commutator 201 which makes one revolution 45 each card cycle. Thus, shaft 571 makes half a revolution for each card cycle or during the interval between which the leading edges of successive cards reach the line of analyzing brushes SB. During one half a revolution of emitter 50 shaft 571, one brush 572 will successively engage spots 9, 8, 7, 6, 5, 4, 3, 2, 1, 0 in synchronism with the arrival of index point positions 9, 8, 7, 6, 5, 4, 3, 2, 1, 0 of a card column at the line of analyzing brushes SM while the opposite brush 572 is wiping the common contact segment 573 of the emitter. During the 55 next half a revolution of shaft 571, the functions of the two brushes 572 will be reversed.

In the instant case, means are provided to compare a four order value, for example, one 60 having a thousands, hundreds, tens, and units order. All the devices related to the thousands order may be distinguished by appending to the general reference character the suffix "th", the hundreds order devices may be distinguished by 65 the suffix "h", the tens order elements by the suffix "t", and the units order devices by the suffix "u".

Each order of the comparing means includes a Wheatstone bridge device W across the opposite sides of which are a pair of parallel magnets 580 and 581. A rectifier 582 permits current to pass only in one direction through magnet 580, and a rectifier 583 permits current to pass in the opposite direction only through magnet 581. Resistances r and r' are of such values

as to cause the potential at opposite sides of the Wheatstone bridge to be equal when the circuit paths through magnets 580 and 581 are simultaneously closed. When the circuit paths of magnets 580 and 581 of a device W are simultaneously closed, the potential at opposite sides of the device W will be equal but oppositely directed, thus preventing flow of current from one side to the other, and neither magnet 580 and 581 will then be energized. If the circuit path of one magnet 580 or 581 alone is made at one time, then the magnet through which the circuit is made will be energized.

One side of each device W leads to a socket 202 and the opposite side to a socket 203. There are thus two sets of sockets 202 and 203, each set comprising four orders. Plug sockets 202 are related to the 11 sorting pocket and sockets 203 to the 12 sorting pocket. Thus, if it is desired to send a card to the 11 pocket if a value A is greater than a value B, entry of value A into the comparison evaluating means is made by way of sockets 202 while if it is desired to send a card to the 12 pocket if value A is greater than value B, then value A is entered by way of sockets 203. As 25 will be brought out later, equal values cause the card to be sent to the reject pocket.

Suppose it is desired to compare a four order or four column value of fields A of the cards with a four order or column value of fields B of the 30 cards and to send the card to the 11 pocket when value A is greater than value B, to send the cards to the 12 pocket when value A is less than value B, and to direct the cards to the reject pocket when values A and B are equal. The plug sockets 195 of the brushes SB for sensing field A are connected by plug wires (not shown) to plug sockets 202, and plug sockets 195 of the brushes SB of field B are connected to sockets 203 of the comparison means. Further, plug wire 196 is removed, switch 198 is closed, and switch blade 199 is set in lower, comparison sorting position, in engagement with switch terminal 199b.

During the passage of index point positions 9 to 1 of a card, the values in fields A and B will be read into the comparing means. It may be noted that 0 index point position of the cards has no effect on the comparing evaluation, since if the value in one compared order is 0 and in the corresponding compared order is greater than 0, the latter value will dominate, while if both compared orders have 0 values, their effects will counteract each other. The 0 value can, therefore, not effect the comparison evaluation.

Assume that the field A of a card contains 55 value 5219 and that field B of the card contains value 4318. The first perforation to be sensed by a brush SB will be the one designating 9 in the units order of value A. When this occurs, the following circuit will be completed (Fig. 4):

Circuit b

From the left side of the line, through commutator 201, contact roll 166 of the analyzer, the brush SB sensing the units order of field A, the 65 connected plug socket 195, a plug connection (not shown) to the units order socket 202 (the right hand one), the left side of units order Wheatstone bridge W-u, rectifier 582, magnet 580-u, resistance r, and to the right side of the 70 line.

Each of magnets 580 is wound on the same core and in the same direction as a magnet 580' while each of magnets 581 is wound on the same core and in the same direction as a magnet 581'. 75

The magnet 580 or 581 may be termed the pick-up coil of a duo wound magnet while the magnet 580' or 581' may be referred to as the holding coil of the duo wound magnet.

5 Circuit b has energized pick-up coil 580-u and the latter closes relay contacts 580a-u. Closing of contacts 580a-u establishes the following circuit through holding coil 580'-u:

Circuit c

10 From the left side of the line, through cam contacts C-6, common wire 585, contacts 580a-u, holding coil 580'u, common wire 586, and to the right side of the line.

15 Cam C for operating cam contacts C-6 is mounted on the shaft of the sorting commutator 201 and closes contacts C-6 before the 9 index point position reaches the analyzing position and until after the 12 index point position passes the 20 analyzing position. The contacts C-6 then open.

20 Pick-up coil 580-u was momentarily energized by circuit b to close contacts 580a-u. Circuit c energizes holding coil 580'-u to maintain contacts 580a-u closed until cam contacts

25 C-6 open. Coil 580'-u, when energized, also closes contacts 580b-u and opens contacts 580c-u.

Closing of contacts 580b-u forms the following circuit:

Circuit d

30 From the left side of the line, through common wire 587, contacts 580b-u, contacts 581c-u, a magnet 990u, and through common wire 588, to the right side of the line.

35 Circuit d energizes magnet 990u to close relay contacts 990a-u, which completes the following stick circuit through magnet 990u.

Circuit e

40 From the left side of the line, through cam contacts C-6, common wire 589, contacts 990a-u, magnet 990u, and wire 588, to the right side of the line.

45 Thus, regardless of subsequent opening of circuit d, magnet 990u is held energized by stick circuit e.

50 The final result of the analysis of a "9" in the units order of field A of a card is the energization of magnet 990u to close relay contacts 990a-u and 990b-u, and to open contacts 990c-u.

55 Similarly, the occurrence of a value in any of the other orders of field A higher than the compared value in the corresponding orders of field B will energize a related order magnet 990. All of the four magnets 990 are thus associated with field A.

60 The next value sensed in the assumed example, is an "8" in the units order of field B of the card. When this happens, the following circuit is completed through pick-up coil 581-u of the device W-u.

Circuit b-1

65 From the left side of the line, through commutator 201, contact roll 166, the units order brush SB of field B, the connected socket 195, the plug connection (not shown) to the units order socket 203 (the right hand one), through rectifier 583, coil 581-u, resistance r', and to the right side of the line.

70 Circuit b-1 energizes coil 581-u to close contacts 581a-u, causing a holding circuit c to form through holding coil 581'-u. Coil 581'-u holds contacts 581a-u closed, also closes contacts 581b-u and opens contacts 581c-u. The 75 closing of contacts 581b-u is ineffective to estab-

lish a circuit d through related units order magnet 960u because contacts 580c-u in series with contacts 581b-u have been opened by previous energization of units order holding coil 580'-u. Opening of contacts 581c-u by energization of holding coil 581'-u opens circuit d of magnet 990u. The latter, however, is maintained energized by stick circuit e.

If the B value in the units order were greater than the A value, then contacts 580c-u would have been closed and circuits d and e would have energized magnet 960u. All of the four magnets 960 are thus related to the respective orders of the B field value.

The comparison of values 9 and 8 respectively in the units orders of fields A and B of a card has resulted in energization of a units order magnet 990u related to the units order of field A. Similarly, comparison of the other corresponding orders of fields A and B, causes the higher value 20 to dominate by energization of the magnet 960 or 990 related to the order in which the dominating value occurs. In the assumed example, where field A bears value 5219 and field B bears value 4318, at the end of the comparing interval, 25 "9" to "1" of a card cycle, magnets 990u, 960h, and 990th will be energized. Neither magnet 960t or 990t will have been energized because the tens order values are equal.

The highest order magnet 990 or 960 which has been energized determines or dominates the control exercised by the comparing means. Thus, if the values had been 5219 and 5218, only units order magnet 990u would have been energized and would control the read-out circuit from the 35 comparing means. In the assumed example of 5219 compared with 4318, although magnet 960h has been energized and dominates magnet 990u, the former magnet is itself dominated by the energized magnet 990th. The contacts 990c and 40 960c guard against the read-out circuit being completed through a lower order magnet when a higher order magnet has been energized. This will be brought out further on by tracing the read-out circuit as though only magnet 990u had 45 been energized.

The comparison values do not include designations 0, 11, or 12 and while the index point positions 0, 11 and 12 for containing these designations are passing the analyzing position, the 50 read-out circuit of the comparing means is formed to control the sorting operation. It will be remembered that during passage of positions 9 to 1 through the card analyzer and the reading into the comparing means of values 9 to 1, 55 that the arms 171 and their associated guide blades 173 have been successively released by cams 170 to successively open paths to sorting pockets 9 to 1. However, with plug connection 196 removed and with switch blade 199 in lower, 60 comparing, position, sorting magnet 175 is not energized coincident with sensing of a perforation, and, therefore, latch plate 177 has not been released to lock the guide blades 173 in any 65 separated relationship.

As the 11 index point position of the card reaches the analyzer, the passage between blades 173 leading to the 11 pocket is open, and as the 12 index position of the card reaches the analyzer, the passage between blades 173 to the 12 70 pocket is open. At either of these times, depending on whether value A or B is greater, sorting magnet 175 is energized. The setting of the comparing means must thus be read out or determined at the 11 and 12 cycle points corre- 75

sponding to the 11 and 12 index position analyzing periods. For this purpose, an "11" emitter 205 and a "12" emitter 206 are provided. These emitters are rotated synchronously with the feed 5 of the card so that as the 11 index point of a card reaches analyzing position, brush 207 of emitter 205 will be engaged by contact segment 208 and as the 12 index point of a card reaches the analyzer, brush 209 of emitter 206 will be 10 engaged by contact segment 210.

Values A and B were read into or entered into the comparison means during the 9 through 15 cycle points. Assume that units order magnet 990u alone has been energized by the comparison 15 evaluating operation. In that case, at the "11" cycle point, the comparison readout circuit is established as follows (Fig. 4) :

Circuit f—“11” read-out

20 From the left side of the line, through common contact ring 211 of emitter 205, contact 208, brush 207, line 212, a magnet 214, common conductor 590, contacts 990b—u (now closed), line 591, contacts 960c—t, line 592, contacts 990c—t, line 593, contacts 960c—h, line 594, contacts 990c—h, line 595, contacts 960c—th, line 596, contacts 990c—th, and through lead 597 to the right side of the supply line.

Thus, when only units order magnet 990u has 30 been energized, the read-out circuit f goes serially through the units order contacts 990b—u and through contacts 990c and 960c of all the higher order magnets.

If any magnet 960 or 990 above the units order 35 had been energized, then one of the 990c or 960c contacts above the units order would have been opened and circuit f could not have been made through the b contacts of units order magnet 990u.

40 Similarly, circuit f can be completed only through the b contacts of the highest order A field magnet 990 which has been energized and through the c contacts of all the higher order magnets.

45 Thus, when two values A and B are compared, of which A is the greater, the highest order in which the A value is superior will control the comparison read-out circuit f to energize magnet 214, as the 11 index point position of the card reaches the analyzer.

If field B contains a value superior to the value 50 of field A, then the determining value is in one of the orders of field B. For example, if field B has a value 2418 and field A has a value 2349, the determining value is the "4" in the hundreds order of the B value. In that case, the pick-up coil 581—h is energized by a circuit b—1, the holding coil 581'—h is energized by a circuit c, and circuits d and e, acting in succession, energize magnet 960h. The magnets 960th and 990th 60 will not be energized, magnets 990t and 990u will be energized, and magnets 960t and 960u will not be energized. A circuit f cannot be formed through the b contacts of magnet 990t because the c contacts, of magnet 960h, which are superior, are open. Neither can a circuit f be formed through the b contacts of magnet 990u because the c contacts of magnets 990t and 960h are open. Accordingly, when the B value is superior, 70 circuit f cannot be formed and magnet 214 is not energized as the 11 index point position of the card reaches analyzing position.

However, as the 12 index point position of the card reaches the analyzer, contact segment 210 75 of the "12" emitter 206 is engaged with brush

208 and the following circuit is completed (Fig. 4) :

Circuit g—“12” read-out

From the left side of the line, through common contact ring 216 of emitter 206, contact segment 210, brush 209, line 217, magnet 218, common conductor 590, the closed contacts 960b—h, then serially through the c contacts of magnets 990h, 960th, 990th, and through lead 597 to the right 10 side of the supply line.

Thus, circuit g can be completed through the b contacts of a magnet 960 only when the c contacts of all the higher order magnets 990 and 960 have not been opened, which is the case only when 15 none of the latter magnets has been energized.

It has been established that when value A is greater than value B, that magnet 214 is energized by a circuit f at the 11 cycle point, and that when value B is greater, magnet 218 is energized 20 at the 12 cycle point.

If magnet 214 has been energized, it closes relay contacts 214a to form the following circuit (Fig. 4) :

Circuit h—Comparison sorting to the 11 pocket 25

From the right side of the line, through contacts 214a, line 215, switch terminal 199b, switch blade 199, sorting magnet 175, switch 198 (now closed), and to the left side of the supply line.

Sorting magnet 175 is thereby energized as the 30 11 index point position of the card traverses the analyzing station. In the manner explained previously, this causes the card to be sorted to the 11 pocket. Thus, the card goes to the 11 pocket when value A is greater.

If magnet 218 is energized by a circuit g because of value B being found greater, the magnet closes relay contacts 218a to form the following circuit (Fig. 4) :

Circuit i—Comparison sorting to the 12 pocket 40

From the right side of the line, through contacts 218a, line 215, switch 199b—199, sorting magnet 175, switch 198 and to the left side of the line.

Sorting magnet 175 is thereby energized as the 45 12 index point position of the card traverses the analyzer and, as previously explained, the card is thereby directed to the 12 pocket. Thus, the card goes to the 12 pocket when value B is greater than value A.

If values A and B are equal, then there will be no closed path through the comparing means for circuit f through magnet 214 or for circuit g through magnet 218 and, accordingly, the sorter 55 magnet 175 will not be energized at all; consequently, the entrance ends of the guide blades 173 will all be below the card and the latter will go to the reject pocket.

If instead of comparing two card fields for 60 values, one such field were to be compared to a preselected value set up on commutator 560, then plug sockets 560' of the latter would be wired to either set of sockets 202 or 203 and the plug sockets 195 of the card field would be wired to the 65 other set of plug sockets 202 or 203. Through emitter E, the values of commutator 560 would be entered, in synchronism with the travel of corresponding value index point positions of the card, into the comparing means to be compared with 70 the values entered from the card field. In the same manner as explained above, the cards would be routed to the 11, 12 or reject pocket depending on the comparison of the values.

The embodiment of the invention shown in 75

circuit form in Fig. 4 has been explained. The embodiment shown in circuit form in Fig. 5 will now be explained. The second embodiment permits of greater flexibility and variety of operation than the first embodiment. In both embodiments, the machine may be set for ordinary, single column control sorting, for sorting to the 11 pocket if one value is greater than another, to the 12 pocket if the value is less, and to the reject pocket if the values are equal. In addition, the second embodiment permits the comparison values, if in one relationship, to cause straight sorting from any selected column, and if the compared values are in different relationships to effect modified sorting. For example, if value A is greater than value B, then the card may be directed to the pocket selected by the analysis of a single card column. If the latter column be designated as field C, then it may be put that when value A is greater than value B, then the card will be sent to the pocket corresponding to the item in field C. However, if value A be less than value B, then field C will not determine sorting but the card will be directed, say, to pocket 12 and if the values be equal, the card will be sent to the reject pocket.

Four different cases possible with the embodiment of the invention shown in Fig. 5 will now be explained:

30 1. Ordinary sorting

As in the embodiment shown in Fig. 4, a switch 199' is set in upper position in which it is in direct connection with the right side of the supply line, a switch 198' is opened, and a plug connection 196' is made between a socket 197' and the socket 195 of the brush SB for sensing the selected card control column. Further, a switch blade 225 is placed in engagement with terminal 226.

Now, when a perforation is sensed by the active brush SB, a circuit is completed through sorting magnet 175 which is similar to circuit a, described in connection with the previous embodiment, except for the inclusion of switch 225-226 in the line between the sorting magnet and plug socket 197'.

2. Sorting to 11, 12, or reject pocket by comparison control

In this case, if value A exceeds value B, the card goes to the 11 pocket; if it is less than value B, the card is sent to the 12 pocket; and if equal, to the reject pocket.

As in the embodiment of Fig. 4, the switch 198' is closed and switch 199' placed in lower position connected to line 215 of the comparing means. If values A and B are to be taken from two card fields, then plug connections to sockets 202 of the comparing means are made to sockets 105 of field A brushes and from sockets 203 of the comparing means to field B brushes.

If one card field is to be compared to a pre-selected value set up on commutator 560, then plug connections from the latter are run to either set of sockets 202 or 203, as required, and plug connections to the other set of sockets are made to sockets 195 of the selected card field.

During the travel of positions 9 to 1 of a card past the sensing brushes SB, the values A and B are entered into the comparing means. At the 70 11 cycle point, if value A has been found to exceed value B, then a circuit the same as circuit f of the previous embodiment, is established, followed by a circuit similar to circuit h, except for inclusion of switch 225-226, to send the card to the 11 pocket.

If value B was found greater than value A, then during the 12 cycle period, a circuit similar to circuit g of the previous embodiment is established followed by a circuit similar to circuit i, except for the inclusion of switch 225-226, to 5 send the card to the 12 pocket. If the values are equal, then neither of above circuits is formed, and the card goes to the reject pocket.

3. Comparison control of ordinary sorting, 12 10 pocket, and reject pocket sorting

In this case, if value A exceeds B, it is desired to effect ordinary sorting of the card according to the designations 9 to 0 of a selected card column which may be termed field C; if value A is 15 less than B, it is desired to send the card to the 12 pocket; and if A equals B, to direct the card to the reject pocket.

For this problem, value A is entered into the comparing means through sockets 202, value B 20 is entered into the comparing means through sockets 203, plug connection 196' between socket 197' and the socket 195 of the brush SB for reading field C is made, switch 199' is moved to upper position, and switch 198' is opened, all as in case 25 1. In addition, switch blade 225 is moved to upper position to engage a terminal 227. Other switch adjustments will be brought out in the further parts of the description.

On shaft 571' of emitter E brushes 572, geared 30 1:2 to the shaft carrying the sorting commutator 201, are also fast the brushes 230' and 231', respectively of commutators 230 and 231.

Commutator 230 has a long contact segment, lying between the points marked 9 and 0, which 35 one of the two brushes 230' of the commutator traverses while the 9 through 0 index positions of a card are traversing the analyzing position. This segment may be called the 9 to 0 segment. After brush 230' leaves the 9 to 0 segment, it 40 wipes a short insulating segment, and then during the 12 cycle point, wipes a contact segment which may be called the 12 segment.

Commutator 231 has three contact segments insulated from each other and arranged to be engaged successively by a feeler 231' of the commutator during the 0, 11, and 12 cycle points, and these contact segments may be termed the 0, 11, and 12 segments.

As indicated in phantom in Fig. 1, a special 50 magnet 232 faces the lower arm of lock plate 177 controlled by armature 176 of the sorter magnet 175. Further, below armature 176 is a pair of normally open spring blades 233 carrying companion contacts 234.

The instant problem involves ordinary sorting according to the designations 9 to 0 of a card column C if a value A is greater than a value B. During the travel of index point positions 9 to 0 of the card past the analyzing station, energization of sorter magnet 175 is effected by completion of the following circuit when a perforation in column C is sensed (Fig. 5):

Circuit j—Ordinary sorting with comparison control

From the right side of the line, through switch 199' (now in upper position), sorter magnet 175, switch blade 225, terminal 227, normally closed relay contacts 236a, the common contact segment 70 of commutator 230, the brushes 230', the 9 to 0 segment of this commutator, a switch 237 (closed for case 3), lead 238, plug socket 197', plug wire 196', the selected socket 195, through the analyzing brush SB connected to this socket, contact 75

roll 166, commutator 201, and to left side of the supply line.

Thus, sorter magnet 175 is energized by circuit *j* upon the sensing of a perforation 9 to 0 in column C. Energization of magnet 175 rocks lock plate 177 (Fig. 1) to retain arms 171 in the upper and lower positions they have reached, and to thereby hold open a path, selected by the value of the perforation in column C, between a pair of 5 guide blades 173 to receive the card as it moves off table 168 and to lead the card to the pocket corresponding to the perforation of column C.

While the 9 through 1 positions of the card column C, selected for controlling straight sorting, are being sensed by the card analyzer, the latter is also sensing the significant 9 to 1 values of fields A and B and entering them into the comparing means.

If value A is greater than value B, then by the 20 time the 0 index point position of the card reaches analyzing position, the dominating magnet 990 will have been energized and its contacts 990b closed to determine the path of the read-out circuit from the comparing means. This 25 read-out circuit is as follows (Fig. 5):

Circuit k

From the left side of the line, through lead 242, switch 241 (closed for case 3), magnet 214, 30 through the comparing means (as explained in connection with the previous embodiment, shown in Fig. 4), and through line 597 to the right side of the line.

Energization of magnet 214 is effected by circuit *k*. In the previous embodiment, magnet 214 had only one pair of relay contacts 214a. In the present embodiment, magnet 214 has, in addition, relay contacts 214b and 214c.

Magnet 214 closes contacts 214a and *b* and 40 opens contacts 214c. Closing of contacts 214a is of no effect because switch 199' is in upper position, closing of contacts 214b (adjacent sorting commutator 201) is ineffective because a switch 243 in series therewith has been set in open 45 position; contacts 214c (at top of Fig. 5) when opened prevent making of a circuit through magnet 232 (Figs. 1 and 5) at the 12 cycle point. Accordingly, the sorting blades 173 are left undisturbed in the positions they were set in by the 50 sensing of the perforation in the selected control column C, and the card goes to the selected pocket 9, 8, 7-1, or 0, as in ordinary sorting.

If value A is less than value B, then by the end 55 of the analysis of the "1" index point positions of the card, a magnet 960 will have been energized and will dominate the read-out circuit from the comparing means as follows (Fig. 5):

Circuit L

60 From the left side of the line, through lead 242, switch 241, switch 245 (closed for case 3), magnet 218, through the comparing means, and through line 597 to the right side of the line.

Magnet 218 when energized by circuit L closes 65 contacts 218a, *b*, and *d*, and opens contacts 218c, before the beginning of the 11 cycle point. Closing of contacts 218a is ineffective because switch 199' is in upper position. Opening of contacts 218c prevents making of the circuit through magnet 232 at the "12" cycle time. The closing of contacts 218b, however, forms the following circuit through magnet 232 during the 11 cycle interval when the 11 contact segment of commutator 231 engages a brush 231' of this commutator (Fig. 5):

Circuit m

From the left side of the line, through special magnet 232 (see also Fig. 1), contacts 218b, a switch 246 (closed for case 3), a line 247, the 11 contact segment of commutator 231, brushes 231', the common contact segment of this commutator, a switch 248 (closed for case 3), and to the right side of the line. 5

Thus, at the 11 cycle time, magnet 232 is energized by circuit *m*. Referring to Figs. 1 and 5, the energization of magnet 232 rocks lock plate 177 clockwise to restore it to initial position. The plate 177 thereby unlocks arms 171 to negative the control thereof which may have been previously effected by the sensing of a designation in the card column C selected for ordinary sorting. As this release of arms 171 occurs during the 11 cycle time, the arms 171 and the guide blades 173 corresponding to index points 9 to 0, and 11 drop at the end of the 11 cycle period, leaving only the blade 173 corresponding to the 12 index point in raised position still held up by its associated cam 170. 10 15 20

As brush 231' leaves the 11 contact segment of commutator 231, circuit *m* breaks and magnet 232 is deenergized. Lock plate 177, however, cannot return to locking position because armature 176 of the sorter magnet is latching the lock plate against counterclockwise motion. 25

During the 12 cycle time, the 12 contact segment of commutator 230 is wiped by a brush 230' and the following circuit is formed: 30

Circuit n—12 pocket selection

From the left side of the line, through contacts 218d (below emitter E), a switch 250 (closed for case 3), the 12 contact segment of commutator 230, brushes 230', the common contact segment of this commutator, normally closed relay contacts 236a, terminal 227, switch blade 225, sorter magnet 175, switch 199', and to the right side of the line. 35 40

Circuit *n* energizes sorter magnet 175 at the 12 cycle time, and as a result, a path to the 12 pocket is opened for the card.

If the values A and B are equal, neither circuit 45 *k* nor *L* will form, and magnets 214 and 218 will not be energized. Consequently, contacts 214c and 218c will still be closed at the 12 cycle point and when the 12 segment of commutator 231 is wiped by a brush 231', the following circuit is 50 formed through the magnet 232:

Circuit o—Cancellation of single column selection

From the left side of the line through magnet 232, contacts 214c and 218c, the 12 contact segment of commutator 231, brushes 231' thereof, the common contact segment of commutator 231, switch 248 (closed), and to the right side of the line. 55

This circuit energizes magnet 232 at the 12 cycle time to cancel the setting of arms 171 which may have previously been effected under control of the selected card column C. Accordingly, all the entrance ends of guide blades 173 drop, and the card goes to the reject pocket. 60 65

In case 3, explained above, when:

A>B, ordinary sorting is effected,

A<B, the card goes to the "12" pocket,

A=B, the card goes to the reject pocket.

4. Comparison direction of ordinary, 11, or reject 70 pocket sorting

Case 4 requires that when:

A>B, the card go to the 11 pocket,

A<B, ordinary sorting be effected,

A=B, the card go to the reject pocket.

The plug connections between sockets 202 and 203 of the comparison means and the sensing devices of values A and B are made as in the previous problem. Likewise, switch 199' is left 5 in upper position, switch 198' is opened, switch blade 225 is left in engagement with terminal 227. The other adjustments will be brought out in the course of the explanation.

When value A is found to exceed value B during 10 the 9 through 1 cycle interval, then magnet 214 will have been energized by circuit k and remain energized till cam contacts C-6 open. Contacts 214a and b will be closed while contacts 214c will be open, as in case 3. As before, switch 199' being 15 in upper position, closing of contacts 214a is ineffective. Closing of contacts 214b completes the following circuit as the 0 index point position of the card traverses the analyzer (Fig. 5):

20 Circuit p

From the left side of the line, through magnet 232, through contacts 214b, switch 243 (closed for case 4), the 0 contact segment of commutator 231, the brushes 231' thereof, the common segment thereof, switch 248 (closed for case 4), and to the right side of the line.

This circuit momentarily energizes magnet 232 as the 0 index point position is passing analyzing brushes SB. The circuit cancels selection of the 30 pockets by the selected column C. When this cancellation occurs, the "11" and "12" guide blades 173 are still in upper positions. The card is required to go into the 11 pocket, and accordingly, the 11 and 12 sorting blades 173 must be 35 retained in upper positions during the 11 cycle period.

When magnet 232 rocked plate 177 clockwise to cancel the previous single column selection, armature 176 ordinarily would be free to move upwardly and latch the plate 177 against counter-clockwise movement, as a result of which the "11" and "12" arms 171 would subsequently be free to move down. It is necessary, however, to retain the 11 and 12 arms in upper position, and this 45 can be done by causing lock plate 177 to move to locking position with respect to the arms 171 at the 11 cycle time. Now, the plate 177 was released from arms 171 by magnet 232 during the 0 cycle time. Energization of magnet 232 by circuit 50 p endures till the 0 contact segment of commutator 231 rides off brush 231', after which the magnet 232 is deenergized. Therefore, plate 177, if unrestrained by armature 176 of the sorting magnet may return to locking position, during the 55 "11" cycle point, to lock arms 171 and blades 173 for opening a path to the 11 pocket.

To leave plate 177 free to return to locking position at the 11 cycle time, sorter magnet 175 must be energized to hold its armature 176 down 60 and away from latching position with respect to the plate 177. This is done as follows:

For case 4, a switch 255 (see middle of Fig. 5) is closed. Cam contacts 256 in series with switch 255 are closed by cam D as the 9 to 0, 11 and 12 65 index point positions of the card traverse the analyzing station. If column C contains a perforation 9 to 0, then sorting magnet 175 will have been energized, and its armature 176 depressed while contacts 256 are closed. Depression of armature 176 closes contacts 234 (Figs. 1 and 5) and with contacts 256 closed, the following circuit is 70 formed (Fig. 5):

Circuit q

75 From the left side of the line, through cam con-

tacts 256, switch 255, relay 236, contacts 234, and to the right side of the line.

Energization of relay 236 opens contacts 236a and closes contacts 236b. Closing of the latter contacts closes the following circuit: 5

Circuit r

From the left side of the line, through cam contacts 256, switch 255, contacts 236b, terminal 227, switch 225, sorter magnet 175, switch 199', and to 10 the right side of the line.

Magnet 175 now remains energized until cam contacts 256 break which is after the 12 cycle time. Since magnet 175 remains energized, contacts 234 remain closed, and consequently magnet 15 236 stays energized to hold contacts 236b of circuit q closed.

It is seen now that energization of magnet 175 under single column control during one of the 20 cycle points 9 to 0 is thereafter maintained by formation of circuits q and r until after the 11 cycle period begins. Thus, when magnet 232 is energized by circuit p and unlocks plate 177 from arms 171 during the 0 cycle time, the plate 177 is not restrained by armature 176 and free to return 25 to locking position at the 11 cycle time, so as to cause sorting of the card to the 11 pocket. This happens when value A is greater than value B.

When value A is less than value B, then magnet 218 is energized by circuit L to close contacts 218a, 30 b and d and open contacts 218c, as in case 3. Closing of contacts 218a is not effective because switch 199' is in upper position; closing of contacts 218b is ineffective because switch 246 is left open for case 4. Closing of contacts 218d is ineffective because switch 250 is left open for case 4. Opening of contacts 218c prevents energization of magnet 232 at the 12 cycle time. Accordingly, the selection through a circuit j, such as previously traced, by column C of the sorting operation remains effective when value A is less than value B, 40 and the card is sent to the pocket corresponding to the designation sensed in the single control column.

When values A and B are equal, neither magnet 45 214 nor 218 is energized, and contacts 214c and 218c remain energized. At the 12 cycle time, circuit o forms, as in case 3, and the card goes to the reject pocket.

The conditions of the different switches for the 50 various cases described in connection with Figs. 4 and 5, are indicated in the following tables:

Fig. 4 Form

Switch	Straight sorting	Comparison sorting	55
198	Open	Closed	
199	Engages 199a	Engages 199b	

Fig. 5 Form

Switch	Case 1	Case 2	Case 3	Case 4	60
198'	Open	Closed	Open	Open	65
199'	Upper	Lower	Upper	Upper	
225	At 226	At 226	At 227	At 227	
237	Open	Open	Closed	Closed	
241	do	do	do	do	
243	do	do	Open	Do	
245	do	do	Closed	Do	
246	do	do	do	Open	
248	do	do	do	Closed	70
250	do	do	do	Open	
256	do	do	Open	Closed	

The operations of the forms of the invention are believed clear from the above detailed description. 75

Instances of the use of the invention are as follows: The cards may contain in fields A the debits of customers, in fields B the credit allowances of the customers, and in fields C the customer account number. Now, according to case 1, ordinary sorting may be effected according to the customer numbers in fields C. In case 2, the cards containing greater values in fields A than in fields B, showing the excess of debit over credit may go to the 11 pocket, cards containing greater values in fields B may go to the 12 pocket, and cards having fields A and B with equal values may go to the reject pocket.

For case 3, if the debit exceeds the credit, the card may be sorted according to its account number in field C; if the credit exceeds the debit, the card may be sorted to the 12 pocket; and if the credit equals the debit, the card may go to the reject pocket. For case 4, if the debit exceeds the credit, the card may be sorted to the 11 pocket; if the credit exceeds the debit, the card may be sorted according to the customer number; and if the debit equals the credit, the card goes to the reject pocket.

It is understood that changes, variations, and departures from the specific illustrated forms of the invention may be made within the spirit and field of the invention, and, accordingly, it is desired to be limited only by the scope of the following claims.

What is claimed is as follows:

1. In combination, electrical value comparing means to compare a pair of values to determine which is the greater, a pair of value representing means, means to transmit the values from said representing means to said comparing means for causing selective electrical operation of the latter according to which of the two compared values is greater, card sorting apparatus to sort the cards to different destinations and including a common controller for determining the destinations to which the cards are sorted, and means controlled by the value comparing means in accordance with the selective operation of the latter to operate the common controller selectively for determining different destinations for a card in accordance with which of the compared values has been found by the comparing means to be the greater.

2. In a machine for operating on record cards bearing value representations, the combination of electrical value comparing means to compare a pair of values with each other to determine which is greater, means to transmit the pair of values, at least one of said values being derived from the record cards, to said comparing means for causing selective electrical operation of the comparing means in accordance with which of the compared values is the greater, card sorting apparatus to sort the cards to different destinations and including a common controller for determining the destinations to which the cards are sorted, and means controlled by the value comparing means for operating the common controller selectively to determine different destinations for a record card depending on which of the compared values has been found by the comparing means to be the greater.

3. In a machine for operating on records bearing value representations, the combination of electrical value comparing means to compare a pair of values to determine which is greater, means to transmit a pair of values represented on a record directly to said comparing means for causing selective electrical operation of the

comparing means according to which of the two compared record values is the greater, sorting apparatus to sort the records to different destinations and including a common controller for determining the destination to which the records are sorted, and means controlled by the comparing means for causing the controller to determine one destination for the record from which the compared values have been taken if one of such values is found by the comparing means to be greater and to determine a different destination for the latter record if the other compared value has been found to be greater.

4. In a machine for operating on records bearing value representing fields, the combination of value comparing means controlled by a pair of value representing record fields to determine the relative magnitudes of the pair of represented values, sorting apparatus to sort the records to different destinations, means under control of the comparing means to cause the sorting apparatus to sort a record to one destination if one value is found greater by the comparing means, means cooperating with the comparing means to cause the sorting apparatus to direct the latter record to a different destination if the other of the compared values is found greater, and means for automatically causing the sorting apparatus to direct the latter record to still a different destination if the compared values have been found equal.

5. In combination; apparatus to sort cards having value representing fields to different destinations, means to compare a pair of values to determine their relative magnitudes, timed means for entering a pair of values, for comparison, into the comparing means at times corresponding to the magnitudes of the values and including means for transmitting at least one of the latter values directly from a value representing field of a card into the comparing means, means for effecting operation of the sorting apparatus to direct a card to a predetermined destination if the compared values agree, and means coating with the value comparing means to modify the aforesaid operation of the sorting apparatus if the values are determined by the comparing means to disagree and in accordance with which of the values is the greater.

6. In combination, apparatus to sort cards having value representing fields to different destinations, means to compare a pair of fields of a card to be sorted to determine the relative magnitudes of the values represented in the latter fields, timed means for entering the values directly from said pair of fields into the comparing means at times corresponding to the magnitudes of the values, means for effecting operation of the sorting apparatus to direct the latter card to a predetermined destination if the values are equal, and means coating with the value comparing means to modify the aforesaid operation of the sorting apparatus if the values are determined by the comparing means to be unequal and in accordance with which of the compared values is found to be greater.

7. In a machine operating on records bearing value representing fields; the combination of means to compare a plurality of fields of a record for relative magnitudes of the values represented in said fields, card sorting apparatus, means under control of the comparing means to effect a sorting operation of the sorting apparatus on the latter record if one of the compared values is found greater, means cooperat-

ing with the comparing means to effect a different operation of the sorting apparatus on the same record if another of the compared values is found greater, and means to effect automatically 5 still another different operation of the card sorting apparatus on the same record if the compared values are found equal.

8. In combination, apparatus to sort cards to different destinations, value comparing means, 10 means to analyze a card while in motion for a pair of values, means under control of the analyzing means according to the analysis of said pair of values to selectively set the comparing means in accordance with the relative magnitudes of said pair of values, and instrumentalities controlled in accordance with the setting of the 15 comparing means for operating the sorting apparatus to sort a card to one of different destinations depending on the relative magnitudes of 20 the compared pair of values.

9. In combination, a sorting apparatus to sort cards bearing value representing fields to different destinations, value comparing means, electrical means to sense a pair of values represented 25 in a pair of fields of a card to be sorted, electrical devices controlled by the sensing means to selectively operate the value comparing means according to which of the sensed card values is the greater, and instrumentalities effective in accordance with the selective operation of the 30 comparing means for controlling the sorting apparatus to sort the latter card to one destination if one card value is found greater and to a different destination if the other compared card 35 value is found greater.

10. In combination; apparatus to sort cards having value representing fields to different destinations, means to compare a pair of values at 40 least one of which is from a value representing card field to determine their relative magnitudes, means for operating the sorting apparatus to direct a card to a certain predetermined destination if the values are equal, means cooperating with the comparing means for operating the sorting apparatus to direct the card to a different predetermined destination if one value is determined to be the greater, and means cooperating 45 with the comparing means for operating the sorting apparatus to direct the card to still another different destination if the other value is found by the comparing means to be greater.

11. In a card sorting machine dealing with record cards bearing values; the combination of value comparing means, a value representing device, electrical means to enter a value from said 50 representing device and a value directly from a record card into said comparing means in opposition to each other, devices for selectively operating the comparing means according to which of the entered values is the greater, card sorting apparatus to sort cards to different destinations, and instrumentalities controlled by the 55 comparing means in accordance with the selective operation of the comparing means for effecting selective sorting operation of the sorting apparatus to sort a card to one of different destinations depending on which of the compared values is the greater.

12. In a card sorting machine dealing with 60 record cards bearing different fields of values; the combination of card sorting apparatus, means for effecting a control of the sorting apparatus in accordance with the value in one field of a card, value bearing means, means controlled by 65 the value bearing means to compare unequal or

equal values from said value bearing means to determine their relative magnitudes, and instrumentalities cooperating with the comparing means for modifying the aforesaid control of the sorting apparatus if the compared values are 5 found equal by the comparing means or if a certain condition of inequality in the compared values is found by the comparing means.

13. In a card sorting machine dealing with record cards bearing different fields of values; 10 the combination of card sorting apparatus, means for effecting a control of the sorting apparatus in accordance with the value in one field of a card, value bearing means, at least one of which is a card field, means to compare and detect unequal values from said value bearing means to determine their relative magnitudes, and instrumentalities cooperating with the comparing means to modify the aforesaid control of the sorting apparatus upon a selected one of the compared values being determined by the comparing means to be the greater. 15

14. In a card sorting machine dealing with record cards bearing different fields of values; 20 the combination of card sorting apparatus for directing the cards to different destinations, value comparing means to determine the relative magnitudes of a plurality of values from said fields of values, means effective upon the value comparing means finding a certain condition of inequality in the compared values for causing the sorting apparatus 25 to send a card to a destination depending on the value in a selected card field, and instrumentalities cooperating with the comparing means for causing the sorting apparatus 30 to send a card to a different destination than the latter upon the comparing means finding a different condition of inequality in the compared values. 35

15. In a machine dealing with record cards 40 bearing values in different fields; the combination of means to compare the values in certain fields of a record card, card sorting apparatus to send the cards to different destinations, means for selecting a destination for the latter card in 45 accordance with the value in a certain field of the card other than any of the compared values, and instrumentalities controlled by the comparing means for canceling the aforesaid selection of the card destination upon a certain relationship 50 of the compared values being found by the comparing means. 55

16. In a machine dealing with record cards bearing values in different fields each of which may bear any one of different values; the combination of means to compare a plurality of fields of a card for values, devices for selectively setting the comparing means according to the relative magnitudes of the compared values, card sorting apparatus to send the cards to different 60 destinations, means to select a destination for a card depending on the value in a field of the latter card other than any of the compared card fields, instrumentalities controlled by the comparing means according to its setting for canceling the aforesaid selection of a destination of the card upon a certain relationship of the compared values being found by the comparing means, and means operable subsequently to the cancellation for operating the sorting apparatus 65 to select a different destination for the card. 70

17. In a machine dealing with record cards each bearing values in different fields; the combination of means to sense a value in a field of a card, means to compare equal or unequal values 75

from fields of said card to effect determination of equal to and greater and lesser than size relations of the compared values, apparatus to direct the cards to different destinations, and means jointly controlled by the comparing means in accordance with the different size relations of the compared values and by the aforesaid sensing means in accordance with the value sensed thereby for controlling operation of the aforesaid apparatus.

18. In a machine dealing with record cards having value fields, each having different value positions to represent different values; the combination of means to sense individual values in a selected field of a card, means to compare values in a plurality of fields other than the preceding field of the same card, card directing apparatus to direct a card to different destinations, and means jointly controlled by the comparing means and by the sensing means for operating the card directing apparatus to selectively direct said card to one of said destinations.

19. In combination; a plurality of value representing means, value comparing means controlled by the value representing means for selective operation in accordance with whether one of the represented values is greater, less than, or equal to another of the represented values, and cyclically operating sorting apparatus to sort records to different destinations and including cyclically operating means for reading out the selective operation of the comparing means at differential times during a cycle depending on the three aforementioned comparative size relations to select different destinations for the records corresponding to the three different size relations of values as determined by selective operation of the comparing means.

20. In a machine operating on records having value fields; the combination of means to compare a pair of opposing equal or unequal values at least one of which is derived from a record field and including means selectively settable in accordance with whether the record field value or the other opposing value is the greater, and cyclically operating apparatus to sort the records to different destinations at differential times during sorting cycles and including cyclically operating means cooperating with the selectively settable means at differential times during a sorting cycle to select one destination for a record if the record field value is the greater and to select a different destination if the other compared value is greater.

21. In a machine operating on value bearing records; the combination of a value representing means, value comparing means to compare a pair of opposing values and including devices to enter a value directly from a record and an opposing value from the value representing means at differential times equivalent to the value sizes into the comparing means to effect selective operation of the latter according to whether the record value or the other compared value is the greater in size, and sorting apparatus to sort the records to different destinations and including means op-

erating under control of the comparing means according to the selective operation of the latter for selecting different destinations for the record according to whether one or the other compared value is the greater.

22. In combination; card directing apparatus including a common magnetic unit energized at differential times to cause the apparatus to selectively direct a card to different locations, a plurality of value representing means, value comparing means controlled by the value representing means according to their represented values for comparing the latter values for relative size, and circuit means conditioned under control of the comparing means according to the value comparison for differentially timing energization of said magnetic unit to cause the apparatus to selectively direct the card to one of the different locations corresponding to the timing of the magnetic unit.

23. In combination; apparatus to sort record cards having value fields which may represent any of different values, instrumentalities for operating the sorting apparatus to selectively sort the cards, means to compare a pair of fields of the card to be sorted to determine which field represents the greater value, and including a pair of devices alternatively effective in accordance with which of the fields has a greater value and means selectively controlled by the said devices, according to which of the two compared fields has the greater value representation, for governing operation of the sorting apparatus by said instrumentalities.

24. In combination; apparatus to sort cards bearing values to different destinations and including a common sorting controller operable to select the destinations of the cards, value comparing means to compare equal or unequal values for size relation, at least one of said values being taken from the card, said comparing means including a magnet energized when one size relation is found by the comparing means and a second magnet energized when a different size relation is found, and means controlled by either one of said magnets alone, according to which one is energized, for operating said common sorting controller to select a destination for the card.

25. In combination; cyclical apparatus to sort cards having value representing fields to different destinations, means for analyzing a plurality of fields of the cards, while in motion, for values during a cycle, value comparing means controlled by the analyzing means for selective operation during the cycle according to the relative magnitude to one another of the plurality of analyzed card values and means controlled by the comparing means, during the same cycle in which the card values were analyzed and compared, for causing the apparatus to direct one or another sorting destination for a card in accordance with different relative magnitudes of the plurality of analyzed card values found by the comparing means.

JAMES W. BRYCE.
